EMMA BOWERMAN, OF NEW YORK, N. Y.

ASH TRAY

Application filed December 21, 1929. Serial No. 415,667.

This invention relates to an ash tray.

The object of the invention is a cheap ash tray, which is easily and quickly manufactured in quantity production and which has a neat and pleasing appearance. The ash trays are intended to be manufactured at such a slight cost that they can be discarded after a single use and, therefore, are particularly adapted for service in hotels and other public places where they will be thrown away after having been used, rather than being emptied and used a second time.

Other objects and features of the invention will more fully appear from the following description and claims, and the accompanying drawing.

While the invention may be illustrated by various embodiments, the following description is intended to set forth a preferred form of the invention, such preferred form, however, to be regarded as typical only of many possible embodiments and the invention is not to be confined thereto.

In the accompanying drawing,

Fig. 1 is a plan or top view of the finished ash tray.

Fig. 2 is a section on line 2—2 of Fig. 1.

Fig. 3 is an enlarged partial section showing the layers of material from which the ash tray is made and showing the adhesive and stiffening material.

Figs. 4 and 5 illustrate the method of manufacturing the ash tray.

From the drawing, it will be seen that the ash tray is formed with a base 1 having upstanding sides 2. The base of the ash tray is preferably formed with embossments 3 to space the tray from the table on which it is to stand, so as to provide an air space below the base to prevent the heat of hot ashes or a burning cigar stub from being transmitted to the table.

The ash tray is preferably made from a plurality of layers of material 4, 5 and 6, which are pressed into shape by the dies 7 and 8. As illustrated in Fig. 3, there are three layers of material, although any number of layers may be used. All of the layers may be of a fireproof material, such as asbestos, or only the inner layer may be of as-

bestos and the intermediate and outer layers may be of a less expensive material.

The usual ash trays have a rather thick rim or upper edge 9 on the sides 2, so that it is rather difficult to break the burning end of a cigar or cigarette off of the stub and also the thick upper edge gives a somewhat unsightly and clumsy appearance to the ash tray. In the present ash tray the upper edge of the side of the tray is of the thickness of only a single layer of the material, which provides a thin rim 9 which is pleasing in appearance, and enables the burning end of the cigarette or cigar stub to be more or less cut off of the stub, rather than torn off. In order to obtain the thin rim for the ash tray, but yet provide strength from the sides of the tray, the layers of material from which the tray is made are so placed that the edge 10 of the side of the outer layer 6 is below the edge 9 of the side of the inner layer, but the full thickness of all of the layers of the material from which the ash tray is made, are present in the lower part of the sides of the ash tray and at the point 11 where the sides join the base 1. If there are more than two layers of material in the ash tray, the edge of the side of each outer layer is successively lower than the edge of the side of the next inner layer. This gives a somewhat tapered appearance, instead of a thick appearance, to the rim of the ash tray and the rim itself is only of the thickness of a single layer of the material.

The layers of material from which the ash tray is made, are preferably held together with an adhesive and, if all of the layers are of a rather weak material, such as asbestos, they are preferably impregnated with a stiffening material. A starch glue or paste has the properties of being both a stiffener and an adhesive and is preferably used, although other chemicals which have only adhesive properties or only stiffening properties may be used in conjunction with each other. If the outer layers of the ash tray are of a stiff material, it will be necessary to use only an adhesive for holding the layers together. The stippling 12 in Fig. 3, denotes either the stiffening material or the adhesive.

material, or the combined stiffening or adhesive material, whichever is used. In some instances asbestos or other paper previously impregnated with either a stiffener or an adhesive or both, is used. Before forming it into shape, the paper is preferably dampened with a liquid, usually water, to soften it and to activate the stiffening or adhesive material.

- 10 In manufacturing the ash trays, blanks of a suitable size and outline are provided. These blanks may be and preferably are, all of the same size, as is illustrated in Fig. 4. The advantages, from manufacturing point 15 of view, of the use of blanks of only a single size will be appreciated as only a single blank cutting machine will be necessary and it will be unnecessary to select different sized blanks from different piles and to assemble them 20 before putting them into the die press.
- The correct number of blanks to be used in the tray are placed in a pile, as is shown in Fig. 4, above the die 8. Suitable spacing pins 13 are preferably placed on the die to position 25 the blanks, so that the edges of the blanks are everywhere equidistant from the edges 14 of the depressed portion of the die. Before the blanks are placed in position on the die, the contacting surfaces are preferably coated 30 with an adhesive and the blanks are impregnated with the stiffening material, if a stiffening material is used. If the material which is used has previously been impregnated with either a stiffener or an adhesive, 35 the blanks are preferably sprayed or dampened with the water or other suitable liquid to soften the material and to activate the stiffener or adhesive. If the inner layer 4 is to be of asbestos and the intermediate and 40 outer layers 5 and 6 are to be of other material, the blanks should be placed on the die, so that the asbestos layer is uppermost. It may be desirable to cut the blanks at the same time that the tray is formed. In order 45 to accomplish this the dies may be provided with cutting blades, for instance the die 7 may be provided with a cutter 15 which fits closely around the die 8, so that as the die 7 is brought down the blanks are first cut and 50 then formed into shape.

As the blanks are properly placed on the die (with the edges of the blanks in line, in the case where all the blanks are the same size), the cooperating die is pressed down- 55 wardly into the other die, as is shown in Fig. 5. If the blanks are properly placed before the pressing, the ash tray will be formed with the thin rim as above described and the upper edges of the outer layers of the material will 60 be successively lower than the rim of the inner layer. This will provide the thin rim of the thickness of only a single layer of material, which is desired.

After pressing the blanks into the desired 65 form, and holding them in position long

enough for the adhesive and the stiffening compound to set sufficiently to hold the layers together and to cause the tray to hold its form, the dies are separated and the ash tray is permitted to stand long enough for the adhesive and the stiffening material to thoroughly set.

Although a preferred form of the invention has been described, it is recognized that modifications may be made and it is, therefore, desired that the invention be construed as broadly as the claims taken in conjunction with the prior art, may allow.

I claim:

1. An ash tray having a base and upstanding sides and comprising an inner layer and an outer layer of material, the edge of the side of the outer layer being below the edge of the side of the inner layer to provide a thin rim of the thickness of only a single layer of material and a plurality of layers below the edge to strengthen the sides at the juncture with the base.

2. An ash tray having a base and upstanding sides and comprising an inner layer and an outer layer of sheet material, the layers being held together by an adhesive, the edge of the side of the outer layer being below the edge of the side of the inner layer to provide a thin rim and to strengthen the sides at the juncture with the base.

3. An ash tray having a base and upstanding sides and comprising inner, intermediate and outer layers, the edge of the side of an outer layer being lower than the edge of the side of the next inner layer, to provide a thin rim and to strengthen the sides at their juncture with the base.

4. An ash tray having a base and upstanding sides and comprising a plurality of layers, the edge of the side of each outer layer being successively lower than the edge of the side of the next inner layers to provide a thin rim and to strengthen the sides at their juncture with the base.

5. An ash tray having a base and upstanding sides formed from a plurality of blanks of the same size and having the upper edge of the outer layer below the upper edge of the inner layer to provide a thin rim of a single thickness of material so as to facilitate the removal of ashes from cigars, cigarettes and the like.

6. An ash tray formed from a plurality of blanks of the same size the top blank or the blank forming the inner layer of the ash tray comprising a blank of asbestos or fireproof material, said ash tray having a base and upstanding sides, the upper edge of the outer layer being below the upper edge of the inner layer to provide a thin rim of a single thickness of material so as to facilitate removal of ashes from cigars, cigarettes and the like, the layer or layers below the edge being provided

to strengthen the sides of the ash tray at the juncture with the base.

7. A device of the character described adapted to be used as an ash tray and discarded after such use, which includes a dished article made from a plurality of superimposed sheets of substantially the same size and having an inner sheet layer and an outer sheet layer; the upper edge of the inner layer being higher than the upper edge of the outer sheet layer to provide a thin rim of the thickness of only a single layer of sheet material, and the concentric layers about said inner sheet layer being adapted to strengthen said layer without adding to the thickness of said thin rim, said thin rim being adapted to facilitate the removal of ashes from cigars, cigarettes and the like.

8. A device of the character described, adapted to be used as an ash tray and discarded after such use, which includes, a dished article made from a plurality of superimposed sheets of substantially the same size and having an inner sheet layer and an outer sheet layer, said inner sheet layer comprising asbestos or fire-proof material, the upper edge of the inner layer being higher than the upper edge of the outer sheet layer to provide a thin rim of the thickness of only

a single layer of sheet material, and the concentric layers about said inner sheet layer being adapted to strengthen said layer without adding to the thickness of said thin rim, said thin rim being adapted to facilitate the removal of ashes from cigars, cigarettes and the like.

9. A device of the character described, adapted to be used as an ash tray and discarded after such use, which includes, a dished article formed by molding a plurality of superimposed sheets of substantially the same size and having an inner sheet layer and an outer sheet layer, the sheets in the finished device being held together by an adhesive, the upper edge of the inner layer being higher than the upper edge of the outer sheet layer to provide a thin rim of the thickness of only a single layer of sheet material, and the concentric layers about said inner sheet layer being adapted to strengthen said layer without adding to the thickness of said thin rim, said thin rim being adapted to facilitate the removal of ashes from cigars, cigarettes and the like.

In testimony that I claim the foregoing, I have hereunto set my hand this 17th day of December, 1929.
